UNITED STATES PATENT OFFICE.

WILLIAM MASON, OF TAUNTON, MASSACHUSETTS.

LOCOMOTIVE-ENGINE.

SPECIFICATION forming part of Letters Patent No. 227,029, dated April 27, 1880.

Application filed January 2, 1880.

To all whom it may concern:

Be it known that I, WILLIAM MASON, of Taunton, of the county of Bristol and State of Massachusetts, have invented a new and useful Improvement in Railway Locomotive-Engines; and I do hereby declare the same to be described in the following specification and represented in the accompanying drawings, of which—

10 Figure 1 is a side elevation. Fig. 2 is a bottom view; Figs. 3 and 4, longitudinal sections of a locomotive-engine "bogie" and its leading-truck provided with my invention, the nature of which is duly set forth in the claims 15 hereinafter presented.

15 The object of the invention is to enable a leading-truck that is "articulated" in itself, as well as in its connection with and adaptation to the forward pair of driving-wheels of 20 the locomotive, to allow its wheels to conform or adapt themselves freely to the various inequalities and undulations vertically of the 25 rails of a railway-track, while at the same time, being entirely rigid laterally, it steadies the engine on a straight line and prevents any 30 wabbling or zigzag movement, and its controlling power of resistance in changing from a straight line to a curve forces the forward 35 end of the machine inward, so as to relieve the flange on the tires on the forward drivers from the outside rail of the curve, and prevents undue 40 wearing of the flange and the cutting of the rail.

In the drawings, A denotes the swiveling 45 truck or "steam-cylinder-supporting bogie," as usually termed, of a "double-bogie locomotive" with its two axles *a b* and four wheels, *c*. The two side frames, *d*, of the bogie are shown as extended in advance of the wheels and supporting the strong bed or cross-piece *e*, by which the steam-cylinders are sustained. The parts *f f*, extending directly under the said bed or cross piece, and to which it is fastened, are provided with recessed boxes or pockets 50 *B*, one of which is shown in longitudinal section in Fig. 4 and in under-side view in Fig. 5. At its rear end each piece *B* is formed or provided with a cylindrical spring-holder, *L*, to receive a helical controlling-spring, *M*, through which and a disk or follower, *p*, an 55 eyebolt, *q*, is extended, as shown in Fig. 6, and

is furnished with a nut, *r*, the said figure being a longitudinal section of the spring and its case or holder and eyebolt and the follower and nut. The pockets or boxes *B* are to receive in their recesses *u* and hold the fulcrum-pivots *g* of the truck. The springs are attached to the truck by means of eyebolts *s* and *q*, in the manner and for the purposes herein-after described.

60 The leading-truck consists of a pair of flanged wheels, *E*, with their axle *D* and two side levers, *C*. The said levers at their forward ends are provided with journal-boxes *u'*, that embrace the journals of the axle *D*. At 65 their rear ends the said levers *C* are loosely connected by hooked bearings *h* to a cross-lever, *i*, which at its middle is united with another such cross-lever, *k*, by means of the link *m*. The lever *k* is suspended at its ends from 70 the springs *o* of the forward wheels of the locomotive by means of screw-bolts, as represented.

75 At a proper distance from the rear ends of the side levers to insure the required division and give the due proportion of the weight to be carried by the forward wheels of the locomotive and the leading-truck are placed the fulcrum-pivots *g*. Furthermore, the two side levers, *C*, are connected near their fulcrum-pivots by a cross beam or bar, *F*, which extends between them at right angles to each, and at 80 its ends is hinged to swiveling-ring-bolts *G* going through the levers *C*, and are secured by nuts *H* screwed on such bolts, but leaving 85 them free to turn in their sockets to allow flexibility.

85 The bar *F* is connected with the two side levers by two bent brace-bars, *I K*, formed and arranged as shown. The brace-bars are pivoted 90 together at their centers, the long or front one being also pivoted to the two side levers, *C*. In other words, the levers are to be so connected or to have the bars *F*, *I*, and *K* so adapted to them as to allow the truck-wheels, 95 while running on the rails, to adjust themselves to the undulations or any variations in altitude of such rails.

When the leading-truck is in its place the 100 eyebolts *s*, that secure the rear bent brace, *I*, to the cross-bar *F*, are united with the eyebolts *q*, that pass through the helical controlling-

springs M, and the fulcrum-pivots g of the side levers enter the recesses u of the boxes B, above described. These recesses or "pockets," as they may be termed, are made longer longitudinally than are the fulcrum-pivots g, in order to allow one of the latter to advance in passing curves either on the right side or the left, as the case may be.

Leading-trucks serve as an addition to the wheel base or support of a railway locomotive-engine, and are of great service in many respects.

My invention operates as follows: The fulcrum-pivots g being held firmly against the rear ends of the recesses u of the boxes or bearing-pockets B by the controlling-springs M, the leading-truck wheels are held rigidly in line with the driving-wheels, and consequently tend to prevent any wobbling or zig-zag motion that the machine is liable to have when running rapidly on a straight track; and as this leading-truck is so flexible that each wheel can rise or fall to a reasonable extent independently of its fellow, and the whole truck is so articulated and equalized in its connections with the driving-wheels that either or both of its wheels can rise or fall, and any of the drivers can do the same. Consequently the disturbing forces are so divided through the articulations among all the wheels that the engine runs much smoother and steadier, comparatively speaking.

In turning curves the driving-wheels of a locomotive are inclined to go in a straight line, and will not vary from it unless forced to do so. Consequently the flanges of the forward drivers are forced against the outside rail of a curve with all the power that is required to slip the opposite drivers on the inside rail. The result is that the flanges of the forward drivers are worn away very quickly and the rails correspondingly cut away. My leading-truck prevents this undue wear in this way. Each of the fulcrum-pivots g, when the engine is on a straight track, acts simply as a fulcrum for the lever; but on a curve such pivot not only serves as such a fulcrum, but as a device for the truck to turn or slide on.

When a curve turns to the left the truck is forced from its line with the drivers and swings to the left, and the center, on which it turns, is the fulcrum-pivot on the left side. Of course the fulcrum-pivot on the right side will be obliged to slide forward in its bearing recess or pocket. This movement of the fulcrum forward is resisted by the power of the controlling-spring on the same side to such an extent as to force the flange of the forward driving-wheel entirely clear of the outside rail, if

desired; or it can be so regulated as to relieve the pressure against the rail to any extent necessary to prevent too much wear. This regulation is effected by simply screwing or unscrewing the nut r, thus giving the controlling-spring more or less resisting power. 60 65

When curves turn to the right the operation is the same; but the truck is forced to swing to the right, and turns on the fulcrum-pivot on the right side, governed by the controlling-spring on the left. 70

The swinging of the truck on pivots situated on each side, like the fulcrum-pivots g, also answers the very important condition of keeping the axle of the truck parallel with the radius of the curve, or nearly so. 75

The two levers C, at their front ends, are connected by a cross-bar, x, adapted to them, to allow of their independent movements, as described, and to keep them duly apart.

What I claim as my invention is as follows, 80 viz:

1. The side levers, C, provided with the axle-boxes u', and fulcrum-pivots g, in combination with plates having pockets u, substantially as described. 85

2. The combination of the side levers, C, provided with fulcrum-pivots g, and the cross or brace bars F, I, and K, adapted and arranged substantially as and for use as set forth.

3. The combination of the controlling-springs 90 M and their housings L with the levers C, and with the recessed boxes B thereof, substantially as described.

4. The combination and arrangement of a leading-truck, constructed as described, with 95 the steam-bogie of a bogie locomotive steam-engine.

5. The combination of the pocketed pieces B, essentially as represented, with the truck and with the rocker-levers C and the cross 100 and brace bars F I K, arranged and adapted substantially as set forth.

6. The combination of the controlling-springs M and their adjusting-bolts g's and nuts thereof with the cross-bar F, brace-bars I K, levers C, and their recessed or pocketed bearings B, applied to the bogie and leading trucks, substantially in manner as set forth. 105

7. The combination of the two sets of springs o M with the bogie-truck and with the levers 110 C, connected by means of and with the leading-truck axle and applied to the bogie-truck, substantially as described, such springs being adapted and arranged essentially as specified.

WILLIAM MASON.
